(57) **CLAIM**

The ornamental design for a multi-component confectionery dispenser, as shown and described.

DESCRIPTION

1.-3. Multi-component confectionery dispenser

1.1 : Perspective

1.2 : Front

1.3 : Back

1.4 : Right

1.5 : Left

1.6 : Top

1.7 : Bottom

Multi-confectionery product dispensers having the following features: a solid confectionery mounted on a housing chamber with an overlying, removable cover retained over deformably compressible liquid confectionery product dispensing chamber by a retaining cap incorporating a nozzle for dispensing the liquid confectionery product onto the surface of the solid confectionery product upon squeezing the dispensing chamber.
